UNITED STATES PATENT OFFICE.

CHARLES GUILLOT, OF PARIS, FRANCE.

APPAREL-CORSET.

SPECIFICATION forming part of Letters Patent No. 657,237, dated September 4, 1900.

Application filed January 19, 1900. Serial No. 2,012. (No model.)

To all whom it may concern:

Be it known that I, CHARLES GUILLOT, of 13 Rue Laffitte, in the city of Paris, Republic of France, have invented a Lady's Garment 5 with Bodice in Place of the Ordinary Corset and Bodice-Lining, of which the following is a full, clear, and exact description.

My invention relates to a garment with bodice to be worn by ladies in place of the ordinary corset, bodice-lining, and orthopedic belt. From a medical point of view this bodice possesses the advantage (by reason of its length and its novel arrangement) of supporting the abdomen and the intestinal organs, and the wearer feels at ease, just as a lady would do when divested of her corset. One of its principal peculiarities is that it completely prevents any obvious protrusion of the abdomen, diminishes the apparent size 20 of the hips, and rounds the figure to an extent hitherto unattained, whereby great elegance and suppleness are given to the female body. On the other hand, with this bodice serving as a lining of the body of the robe, 25 the breasts are located above the stiffened or boned part, and consequently are not compressed, and therefore entirely preserve their firmness. This bodice, which can be sold separately from the robe, can be worn with 30 any description of costume and advantageously replace the usual corset and the orthopedic belt, which generally cause suffering to women. To this end, in order to support the breasts and not compress them, I cut away 35 the part above the stiffened or boned part and apply thereto a strip of lace, which supports the breasts when it is desired to make use of the said bodice with any description of ready-made costume.

With a view to making my invention clearly understood I will describe the same by reference to the drawings annexed to this specification, and in which—

Figure 1 represents a schematic view of 45 a gown, the lining of bodice being shown in the dotted lines. Fig. 2 represents the bodice-lining independent of the gown, the lining being cut out above the boned part and replaced by the strips of lace *a*, prop-

ping up the breasts when it is desired to 50 make use of the said bodice with any ready-made costume.

The said bodice *B*, the material forming the back of which is cut slanting, so as to allow it to easily follow the movements of the body, 55 consists only of twelve bones *b*—four in the back, four in the front, and two on each side. It is provided with a double lacing *c c*, adjusted on the front plaits. It is fastened by means of straight busk *g*, slightly bent at its 60 lower part, which, in combination with the strip *d*, helps to lessen the obvious size of the hips, allowing at the same time to support the abdomen, the side pieces *e* being arranged in such a manner as to draw in the waist in 65 front. So that the garment thus made up or the bodice used independently of the gown *A* should have no tendency to work up, the straps *f* are added and fastened to the edge of the bodice. It will be seen that there is 70 no opening in the back of this bodice, the back and sides being continuous. The front is in two parts, as shown, each part being provided with one part of a busk for fastening them together. Between each part of the 75 front and the adjacent side portion there is a row of lacing, running from close to the lower end of the busk up to a point near the upper end of one of the bones *b*.

The bodice, which is preferably made of 80 silk or other light strong fabric, comes well down over the hips of the wearer and can be drawn tightly across the hips and abdomen by means of the lacing.

I claim—

An improved bodice, composed of a back portion cut bias and provided with four bones, side portions continuous with the back portion and each provided with two bones, elliptical side pieces *e* below the side portions, 90 strips *d* below the side pieces, adapted to be drawn tightly around the hips, one of the bones on each side running down across the piece *e* and strip *d* over the hips, a front portion made in two parts each carrying one part of a busk 95 extending down as low as the lower edge of the strip *d*, and lacings extending continuously between the side portions and strips *d*

and the adjacent part of the front portion, whereby the waist will be drawn in in front, the size of the hips lessened, the abdomen supported, and elegance and suppleness improved to the figure of the wearer.

The foregoing specification of my lady's garment with bodice in place of the ordinary

corset and bodice-lining, styled "robe mystérieuse," signed by me this 9th day of January, 1900.

CHARLES GUILLOT.
